UNITED STATES PATENT OFFICE.

GEORGE AINSWORTH, OF GREAT NECK, NEW YORK.

DESIGN FOR A HUSK FOR LIGHTING FIXTURES.

Application filed May 25, 1923. Serial No. 6,277. Term of patent 3½ years.

To all whom it may concern:

Be it known that I, GEORGE AINSWORTH, a citizen of the United States, and residing at Great Neck, in the county of Nassau and State of New York, have invented a new, original, and ornamental Design for a Husk for Lighting Fixtures, of which the following is a specification, reference being had to the accompanying drawing, forming part thereof.

Fig. 1 is a side view of a husk for lighting fixtures showing my new design;

Fig. 2 is a bottom plan view of the same.

I claim:

The ornamental design for a husk for lighting fixtures, as shown.

GEORGE AINSWORTH.
